UNITED STATES PATENT OFFICE.

CHARLES S. JOHNSON, OF MARCY, NEW YORK.

WASHING-MACHINE.

1,172,462.

Specification of Letters Patent. Patented Feb. 22, 1916.

Application filed January 31, 1914. Serial No. 815,819.

To all whom it may concern:

Be it known that I, CHARLES S. JOHNSON, a citizen of the United States, residing at Marcy, in the county of Oneida and State 5 of New York, have invented certain new and useful Improvements in Washing-Machines, of which the following is a specification, reference being had therein to the accompanying drawing.

10 My invention relates to a washing machine, and I declare the following to be a full, clear, concise, and exact description thereof sufficient to enable anyone skilled in the art to which it appertains to make and 15 use the same, reference being had to the accompanying drawings in which like reference characters refer to like parts throughout the specification.

The object of the invention is to provide a 20 simple, efficient washing machine that will be of especial service in cleansing garments, fabrics and delicate goods, such as doilies and laces, without tearing or injuring the same. The machine will be found of inestimable value to housewives, who do their 25 own weekly washings. The machine may also be built on a larger scale for use in laundries and hotels. These and other features will be observed by referring to the 30 drawings in which:

Figure 1 is a side elevation of the machine; Fig. 2 is a vertical section of the machine, showing parts in elevation; Fig. 3 is a fragmentary view in perspective of a 35 lever employed; Fig. 4 is a plan view of a disk employed; Fig. 5 is an enlarged detail view of a cap employed; Fig. 6 is a plan view of the machine; Fig. 7 is an enlarged fragmentary view in perspective, showing 40 the detachable engagement of the angle irons; Fig. 8 is an enlarged fragmentary sectional view, showing parts in elevation of the machine; Fig. 9 is a vertical sectional view, showing parts in elevation, of a modified construction of the machine.

Referring more particularly to the drawings, the washing machine embodies a cylindrical shaped metal tub —1— having a flanged upper portion 2 adapted to form a 50 shouldered seat for the reception of the edge of the cover 3. The cover 3 has secured thereto a circumferential ring 4 and a sleeve 5 disposed in the center of the said cover 3. The aperture 6 of the sleeve 5 alines 55 with an aperture 7 in the said cover 3, whereby to permit the vertical movement

therealong of the rod 8, which is threaded at one end 9 for the mounting of the nut 10, that holds the rod 8 from sliding inward because of the tension thereon of the conical 60 spring 11. The opposite end of the rod 8 is secured to the center of the disk 12, provided with a flange portion 13, whereby to guide the disk 12 in its vertical movements hereinafter described. The disk 12 is also 65 provided with concentric apertures, so to permit of the passage of water thereby. The conical spring 11 has one end secured to the disk 12 and the other end secured to the cover 3. The said spring 11 is conical in 70 shape to permit of the compression of the spring 11 into a single horizontal plane, whereby the disk 12 may have a maximum vertical movement. The cover 3 is held rigidly in detachable assembled position by 75 the angle irons 15 which have certain of their ends loosely mounted to the reduced portion 16 of the cap 17. The said ends are enlarged and have circular apertures adapted to be detachably mounted to said reduced 80 portion 16 between the nut 18 screw threaded to the lower end 19 of the cap 17 and the shoulder 20 formed upon the said cap 17. The opposite ends 23 of the angle irons 15 engage in a detachable manner the slots 20^a 85 formed in the upper ends of the angle irons 21, that extend along the outer surface of the cylindrical tub —1— and below to form the standards or legs 22. The cap 17 is provided with a threaded orifice 24 and with 90 winged members 25—25, whereby the said cap 17 may be easily turned upon the threads 26 of the sleeve 5. The vertical movement of the cap 17 will cause a similar movement of the adjacent ends of the angle irons 15, 95 whereby the opposite ends 23 of the angle irons 15 will move in the opposite direction to that in which the ends adjacent the cap 17 move, so that when assembling the cover 3, and the cap 17 are screwed down tight, the 100 ends of the angle irons 15, adjacent the cap 17, will lie below the upper plane of the circumferential ring 4, upon which the said angle irons 15 fulcrum, and thereby cause the ends 23 of the angle irons 15 to move 105 upward to pinch or engage in a secure manner the slots 20^a of the angle irons 21. The angle irons 15 are so bent at 27 that all lie from portion 27 to their outward ends 23 in the same common plane. The said ends 110 23 of the angle irons 15 are limited, furthermore, in their movement by the straps 28

secured to the top surface of the cover 3. There is also a vent or cock 29 in the cover 3.

Below the disk 12, there is disposed a vertical movable disk 30, having the concentric apertures 31 for the passage of the water. The disk 30 has a central boss 32 and is secured to the upper end of a rod 33, which extends down through an orifice in the bottom 34 of the tube —1—, which orifice is made water tight by the employment of the stuffing box or gland 35 and the packing 36. The lower end of the rod 33 passes through the guide sleeve 37 formed upon the brace 38 that is secured at either end to any two of the legs 22, that are diagonally opposite. The rod 33 is actuated in a vertical manner, whereby to move the disk 30, by the hand lever 39 fulcrumed at 40 to the links 41—41, which are pivoted at 42 to the depending lug 43 of the brace 44 secured at either end to the legs 22, thus constituting a movable fulcrum. The hand lever 39 is bifurcated at 45 to form the forks 46 having holes 47 for the assembling 25 of a pivot 48, that passes through the rod 33.

To operate the machine, the cover 3 is first removed by unscrewing the cap 17 a short distance in order to relieve the tension on the angle irons 15, whereby the cover 3 may be turned, so as to permit the ends 23 of the angle irons 15 to clear the slots 20^a, whereupon the cover 3, together with the connected parts, that is the disk 12, spring 11, etc., may be taken from the tub —1—, 30 which is then filled, preferably up to the line 50—50 illustrated in Fig. 2, with water in which there has been disposed a washing powder or some like cleansing substance. The soiled or dirty clothes are placed into 40 the tub —1— upon the disk 30. The cover 3 is replaced and turned until the ends 23 of the angle irons 15 engage the slots 20^a of the angle irons 21, whereupon the cap 17 is screwed down tight to the cover 3 in order 45 to cause the ends 23 of the angle irons 15 to pinch the slots 20^a of the angle irons 21, and thus hold the cover 3 in a secure manner. A packing 51 is employed to make a water tight joint between the edge of the 50 cover 3 and its seat formed by the flange 2. The hand lever 39 is now worked back and forth to thereby cause the alternate elevation and depression of the disk 30. As the disk 30 rises, it pushes the clothes upward 55 against the upper disk 12 which yields or recedes into the position indicated by the dotted lines in the Fig. 2. This yielding of the disk 12 allows the clothes to be ele-

vated above the water line, whereby the pressure of the disks 12 and 30 will cause a 60 wringing of the clothes in the upper location of the tub —1—. The successive descent of the disk 30, however, followed by the like movement of the clothes, which are urged downward by the disk 12 under the 65 pressure of the spring 11, causes the water, which is set in agitation by the descent of the disk 30 to boil up through the clothes and remove the dirt and grease therefrom in a thorough manner. This process of alternately soaking and wringing the clothes is very effective in the cleansing of the same, and a few strokes of the hand lever 39 is sufficient for the purpose. The clean clothes may then be removed and replaced by the 70 dirty or soiled ones. The dirt will settle to the bottom of the tub —1—, where the same may be drawn off through the faucet 52.

By permitting the disk 12 to yield, the pressure on the garments in the tub —1— 80 is a gradual pressure, whereby the most delicate fabrics can be washed without injury to the same.

Fig. 9 illustrates a certain modification in that the parts, which are similar to those 85 of the former construction are reversed. This construction avoids the use of the stuffing box or gland 35. The lever 60 is fulcrumed at 61 to the link 62 pivoted at 63 to the upward extension 64 of the angle iron 90 21. The rod 33 is pivoted at 65 to the lever 60.

Having thus described my invention, what I claim as new and desire to secure by Letters Patent is:

In a washing machine, the combination of a tub having a detachable cover, a rod slidably mounted in said cover, a disk mounted to the end of said rod, a spiral spring mounted on said rod between said disk and said cover, whereby to permit said disk to yield, a second disk having concentric apertures, a rod attached to said second disk, a gland in the base of said tub for the vertical reciprocation of said second named 105 rod, and a lever pivoted to links constituting a movable fulcrum for actuating said second named rod and said disk, whereby to wring the clothes placed between the said disks, above the water line in said tub. 110

In testimony whereof I have affixed my signature in the presence of two witnesses.

CHARLES S. JOHNSON.
